UNITED STATES PATENT OFFICE.

HERBERT L. ROBERTS, OF TORONTO, ONTARIO, CANADA, ASSIGNOR TO BUSINESS SYSTEMS, LIMITED, OF TORONTO, ONTARIO, CANADA, A CORPORATION OF CANADA.

AUTOGRAPHIC REGISTER.

Application filed September 24, 1918. Serial No. 255,482.

To all whom it may concern:

Be it known that I, HERBERT L. ROBERTS, a subject of the King of England, residing at Toronto, in the Province of Ontario, Dominion of Canada, have invented certain new and useful Improvements in Autographic Registers, of which the following is a full and clear specification.

The present invention relates to improvements in autographic registers of the type in which a plurality of webs of paper containing printed forms, such as for sales slips, and longitudinally spaced pairs of register perforations are periodically engaged by aligning pins to relatively register the superposed forms at the completion of each recording and feeding operation, so as to insure the detachment of slips of uniform length corresponding properly with the printed forms contained thereon.

The present invention relates more particularly to an improvement upon the machine covered by my application filed July 27th, 1918, Serial No. 247,039, which comprises suitable feeding mechanism for advancing the superposed webs of paper over a writing table from supply rolls supported beneath the writing table, and feed arresting means controlled by automatically acting feeler and aligning fingers which operate upon the moving webs and move into the register openings of the webs for tripping the feeding mechanism and releasing its hold upon the webs to permit the webs to be drawn backwardly over the writing table until their backward movement is arrested by the engagement of the walls of the register openings with the feeler and aligning pins.

The purpose of the present invention is to simplify and improve the machine of said application by eliminating the automatic trip which releases the aligning pins and drops them upon the paper when the movement of the feeding mechanism is started. This is accomplished by providing means for shifting the aligning pins out of alignment with the register openings when they are withdrawn from said openings, so they will engage and rest upon the webs and be sup-

ported thereby in their elevated position until the next succeeding feeding operation shifts the next pair of register openings into position to receive the pins which act to arrest the feed and register the webs.

In order that the invention may be fully understood it will first be described with reference to the accompanying drawings and its novelty afterward pointed out more particularly in the annexed claims.

Figure 1 is a side elevation of an autographic register embodying the present invention;

Figure 2 is a plan view of the same;

Figure 3 is an enlarged detail longitudinal sectional view showing one of the slotted supporting brackets for the gravity take up rolls;

Figure 4 is an enlarged vertical transverse sectional view, taken on the line 4-4 of Figure 2;

Figures 5 and 6 are detail vertical sectional views of the automatic feed and registering devices, said views being taken respectively, upon the section lines 5-5 and 6-6 of Figure 4.

In the embodiment of the present invention, shown in the accompanying drawings, the machine is built up upon the usual side frames 1 and 2, connected by strengthening cross rods or tie bars, such as shown at 3 and by the operating parts hereinafter referred to. 5 is a table frame pivotally mounted at its rear end upon a rod 6, mounted in the upper edges of side frames 1 and 2 and formed with downwardly presented side flanges that snugly fit over the upper edges of the side frames 1 and 2 when the table is in lowered operative position. The rear end of the table is cut away and mounted in this cutaway portion are downwardly presented bracket flanges 14 and 15, formed with inclined slots 16, in which are freely mounted the journal ends of gravity idler rolls 20. These rolls 20 serve the double function of guiding the webs of paper from the supply rolls (presently referred to) to the writing table, and providing automatic means for moving the webs rearwardly over the table when the feed mechanism releases them for 100

the purposes hereinafter explained. The number of idler rolls 20 depends upon the number of webs that are to be handled in the machine. The accompanying drawings 5 show four such rolls.

The previously printed and properly perforated webs or sheets are mounted in roll form as commonly practiced in this art. The rolls of prepared webs, preferably upon 10 tubular spindles, such as is usually made of paper board, are mounted between bearing cones arranged in pairs. Each pair of bearing cones comprises a stationary flanged head 25, mounted upon a rigid pin or lug, 15 in one side frame and a movably mounted flange head 26, mounted upon the inner end of a sliding rotating pin 27, extending through bearing 28 in the opposite side frame and supporting an expansion spring 29 be- 20 tween the head 26 and the side frame for holding the head yieldingly in engagement with the tubular roll spindle. These spring pressed rotating bearings for the rolls cause the rolls to be pressed against the stationary 25 bearing heads with sufficient pressure to properly retard the feeding movement and since all of the rolls are pressed toward the same side of the machine and are supported by the same form of devices it will be seen 30 that the side edges of the superposed web of paper will be properly aligned.

Secured to the table side flange at the right are a pair of outwardly projecting bracket arms 35, formed with vertical slots 37 adapted to receive the rod 40, which supports the roll of the required number of webs of carbon paper. These carbon webs are all wound upon the same rod, as is usual.

60 is a flanged cover plate pivotally 40 mounted upon the rod 6 and formed with downwardly presented side flanges adapted to fit over the side flange of table 5 at one side and the carbon roll support at the opposite side. This cover plate forms a top 45 housing for the carbon sheets and a marginal housing for the superposed webs of paper, the plate being centrally cut out as shown at 61 to expose the central zones of the successive register blanks of the top- 50 most web.

Mounted between the side frames at their forward or delivery ends is a suitable frame consisting of side plates 75 braced by the suitable tie plates, in which is mounted the 55 web feeding and aligning mechanisms which will now be described.

The upper feed roller 80 is journaled in the upright side members 75 just above the plane of the feed of the paper webs from 60 the writing table. This upper roll 80 is formed with annular feed ribs or collars 81 a short distance from its ends, a series of gear teeth 83 at one end, and a combined ratchet and driving gear 84 at its opposite 65 end. A crank handle 85 is secured to the

projecting journal end of roll 80 at the left hand side of the machine, by which the feeding mechanism is manually operated. A gravity stop dog or pawl 86 is pivoted at 87 to the frame piece 75 in position to constantly engage the combined ratchet and drive gear 84 to prevent backward rotation of the same. 70

90 is the lower feed roller freely journaled in a pivoted carrying frame consisting of 75 side plates 91, connected by tie rods which allow a slight relative yield between the two side plates. The side plates are independently pivoted in the upright frame plates 75, 75 upon pivots 95. Tension 80 springs 96 connect the frame plates 91 with the side frames 1 and 2, to yieldingly hold the lower feed roller in peripheral engagement with the annular feed collars of the upper roll; the opposite ends of lower feed 85 roller being acted upon independently to insure accuracy in the feeding operation.

The rock shaft 97 has rigidly secured to it two bifurcated rock arms 98, which engage plates 91 of the pivotally mounted 90 spring actuated frame of the lower feed roll. This rock shaft also has rigidly secured to it a rock arm 100, which projects upwardly and backwardly over the gear teeth 83 of the upper feed roll 80. To the 95 free end of this rock arm 100 is pivotally mounted at 101 a dog 102, engaged by a spring 103, carried by arm 100. This dog 102 is designed to move into engagement with the series of gear teeth 83 when released by the controlling mechanism hereinafter described, for the purpose of positively rocking both side plates 91 of the frame carrying the lower feed roller to separate the feed rolls and release the webs 105 therefrom.

105 is a sectional horizontal plate formed with downwardly projecting end flanges 106, through which project the inner ends of pivot bolts 95. The flanged ends of the 110 plate 105 are secured upon these pivot bolts by suitable nuts. This plate 105 forms a short horizontal extension of the inclined writing table for accurately presenting the webs of paper to the feeding mechanism and 115 the controlling and registering devices. Plate 105 is formed with vertical slots 108 for the reception of the feeler and aligning fingers 110 which will now be described.

Journaled in the upright frame parts 75 120 above the feed rollers above described, is a rock shaft 115, carrying loosely mounted rearwardly presented arms 116 and 117, upon which are loosely hung the feeler and aligning fingers 110. These fingers 110 reciprocate freely and vertically in suitable guides 111, secured to the upright tie plate 76, and are adapted, when released, to press lightly upon the passing webs of paper and to enter the register openings in the webs, and pro- 125 130

ject into the slots 108 of plate 105 as will hereinafter be explained.

The arms 116 and 117 are loosely mounted upon shaft 115 and provided with limited 5 "lost motion" thereon by any suitable means such as the set screws indicated at 116^a and 117^a engaging slots or flats formed in shaft 115 as indicated by dotted lines in Figure 4. This mounting of arms 116 and 117 is the 10 same as in my application Serial No. 247,039, above referred to. Torsion springs 118 loosely surround the shaft 115, engaging brackets 119 at one end and an arm 116 or 117 at the other end.

15 The shaft 115 carries centrally between its ends a rigidly attached collar 130 having a laterally projecting pin 145 which operates in notch 141 of vertically movable manually operated plate 140. The plate 140 reciprocates in suitable slots formed in bracket 142 and housing plate 77, and is provided with a hand flange 143. By depressing plate 140 the shaft 115 is rocked in opposition to 20 springs 118 for the purpose hereinafter explained.

25 150 is a two armed light leaf spring centrally secured at 151 to the inner face of tie plate 76, and having its opposite end bowed slightly and presented in front of the aligning fingers 110 to give them a normal spring tendency to move rearwardly at their lower ends; the guiding supports of said fingers 110 being such that the lower web engaging portions of the fingers are free to move forward and backward approximately parallel 30 with the plane of feed in addition to their up and down movements.

The purpose of this backward spring movement of fingers 110 is to automatically 35 move the fingers out of vertical alignment with the register openings of the web and the slots 108 of plates 105 so that the fingers will rest upon imperforate portions of the web after each registering operation for 40 holding the feed throw-out inactive and the fingers in position to accomplish their next registering operation. When fingers 110 are thus supported in elevated position and the webs are moved forward by the feed mechanism 45 the friction of the webs on the lower ends of the fingers moves them forward against the action of spring 150 until they are arrested by engagement with under roll 90 and held in that position directly over 50 slots 108 in readiness to drop into the next register openings of the webs.

55 Adjustably mounted upon the shaft 115, adjacent one end, is an adjustable cam 165, which operates in a yoke 170, which straddles and is supported by the cam 165 and is pivoted at its lower end 171 to the free end of the dog 102, above referred to. The spring 103 acting through the dog 102 causes yoke 170 to closely follow the cam 165. The 60 purpose of the cam 165 and yoke 170 is to

raise or lower the dog 102 with reference to the ratchet wheel 83. When the operating plate 140 rocks shaft 115 for raising feeler fingers 110, causing them to be supported in elevated position, the cam 165 70 acting through yoke 170 raises dog 102 away from the ratchet teeth 83, thereby permitting the springs of the lower feed roller to throw that roller into operative relation with the upper feed roll.

75 The operation of the improved register may be briefly explained as follows:

The several properly prepared webs are led from their supporting rolls over the guiding and take up rolls 20 to the writing 80 table 5, over which the several webs of carbon paper are passed from the carbon supporting roller. The carbon sheets being interposed between the record webs and secured against displacement in the manner 85 well understood in this art.

The several superposed webs are threaded between the upper and lower feed rolls and adjusted into registered position with the aligning pins 110 passing through the registering openings of the several webs. In 90 this adjustment at the start the feed rolls are spread apart by pressure on rock arm 100 so that the webs may move freely in the machine and with relation to each other. 95 With the webs properly positioned and the feed rolls thrown into action, the operator makes his record of a sale or other transaction of which he desires a manifold record, and then by rotating the crank 85 clockwise, 100 feeds the several webs over the writing table and out of the delivery end of the machine. As the webs are fed forward the friction of 105 paper on lower ends of fingers 110 moves the fingers against roll 90 where they remain supported above slots 108 in plates 105 until the next pair of register openings reach the pins and they drop through said openings into slots 108, which action permits the 110 spring actuated rock shaft 115 to move and lower the dog 102 into mesh with the rotating gear teeth 83, which draws rearwardly on the rock arm 100 for spreading apart the feed rolls and releasing the record webs from the grip of the feed mechanism. At 115 the completion of this feed arresting operation, the dog 102 continues in engagement with the gear teeth 83, thereby arresting the rotation of the feed rolls in a feeding direction and in co-operation with the dog 86 in 120 its engagement with gear 84 locking the feed mechanism in the spread apart condition.

When the superposed webs are released 125 from the feed rolls in the manner explained they are all pulled backwardly over the feed table by the idler take up rolls 20, moving by gravity in their inclined slots, each paper web being independently pulled backwardly until it is arrested by the engagement of the 130

walls of its registering perforations with the aligning pins. In this manner all of the webs are brought into accurate alignment and registry, any slight inequality in the 5 action upon one or more of the webs being completely corrected by the registering operation. In this way there is no danger whatever of accumulating error in registry of the record webs.

10 Immediately following the registry of the webs, as explained, the operator depresses the plate 140, with the result that dog 102 is first raised out of engagement with gear 83 to permit the lower feed roll to spring 15 back into feeding relation with the upper roll to grip the webs between the rolls, and immediately following the grip of the webs by the feed rolls, the aligning and registering pins are withdrawn from the register 20 openings and rest upon the webs by reason of the action of spring 150, and support the rock shaft and connected parts in retracted position. The projecting manifold records are then to be severed from the webs by any 25 suitable means. In the machine illustrated I have employed the tie plate 77 as a cutting bar up against which the projecting slips can be torn off. In this tearing off operation the webs are rigidly held against movement 30 by the grip of the feeding rolls.

When the succeeding record is made upon the superposed webs the operation is repeated.

While the present invention has been described in connection with a machine in which the registering operation is accomplished by a rearward pull upon the webs when released from the feed, as covered broadly by my above named application Ser. 35 247,039, I would have it understood that I do not intend to limit myself to such a registering operation but intend to claim my improved registering devices in their broadest application whatever may be the direction 40 of movement of the web or the means employed for moving it in the registering operation. Thus, the important features of 45 the aligning or registering fingers which are supported in inactive position by their engagement with imperforate parts of the webs, may be employed in a machine in which the registry of the webs is accomplished by the arrest of movement of the web by its engagement with the fingers, without 50 regard to throwing out of action the feeding mechanism or any other parts controlled by the feeler fingers.

I claim:

1. In a machine of the character described, 55 the combination of web feeding means, with a web-registering member movable perpendicularly to the plane of feed of the web when registering and automatically movable parallel with said plane of feed when returned from registering position.

2. In a machine of the character described, the combination of web feeding means, with a web-registering member movable perpendicularly to and parallel with the plane of feed of the web, and a mounting for said member in fixed relation to said feeding means.

3. In a machine of the character described, the combination of web feeding means, with a web-registering member movable approximately perpendicularly to the web path and yieldable in the web path.

4. In a machine of the character described, the combination of web feeding means, with a web registering member movable approximately perpendicularly to the web path and yieldable in the web path, and a stop limiting said yielding motion.

5. In a machine of the character described, the combination with means for feeding a web having longitudinally spaced registering perforations, with a web-registering pin movable approximately perpendicularly to the web path into and out of the web perforations and yieldably mounted upon its support to move parallel with the web path and engage and be carried by an imperforate portion of the web in its feeding movement.

6. In a machine of the character described, the combination with means for feeding a web having longitudinally spaced registering perforations, with a web-registering pin movable approximately perpendicularly to the web path into and out of the web perforations and yieldably mounted upon its support to engage and be carried by an imperforate portion of the web in its feeding movement, and means for limiting the movement of said pin in the web path.

7. In a machine of the character described, the combination with means for feeding a web having longitudinally spaced registering perforations, with a web-registering pin mounted upon a supporting member to move approximately perpendicularly to the web path and to yield in the direction of feed in the web path, a spring acting upon said registering pin, and a stop for limiting the yielding motion of said pin in the web path; whereby said pin will rest upon an imperforate portion of said web and be moved in the web path against said limiting stop in readiness to enter a registering web-perforation.

8. In a machine of the character described, the combination of web feeding means, with a spring-actuated web-registering member movable perpendicularly to the web path and yieldable in the web path, and manually operated means for moving said registering member into initial position.

9. In a machine of the character described, the combination of means for feeding a web, with a web-registering member mounted ad-

1. In a machine of the character described, the combination of means for feeding a web, with a web-registering member adjacent to the plane of feed of the web and movable through and parallel with the web plane, manually operated means for moving said member into initial position, and 5 independent spring devices acting upon said registering member in two directions.
2. In a machine of the character described, the combination of means for feeding a web, with a web-registering member 10 movable perpendicularly to and parallel with the web path, independent spring devices acting upon said registering member in two directions, and manually operated means for moving said member out of its registering engagement with the web.
3. In a machine of the character described, the combination of means for feeding a perforated web, with a web-registering member yieldingly mounted adjacent to the 15 plane of feed of the web, said member being movable through the web plane into and out of a web perforation and in the web plane into and out of the vertical transverse plane of registration.
4. In a machine of the character described, the combination of means for feeding a perforated web, with a transversely yielding web-registering member mounted adjacent to the plane of feed of the web and normally supported by an imperforate portion of the web and movable through the web plane into a registering perforation.
5. In a machine of the character described, the combination of means for feeding a perforated web, with a web-registering member yieldable in the web plane and normally supported by the web and movable perpendicularly of the web plane into and 40 out of a registering perforation, and manually operated means for disengaging said member from the web perforation.
6. In a machine of the character described, the combination of means for feeding a perforated web, with a web-registering member mounted adjacent to the plane of feed of the web and movable through said web plane into engagement with a web perforation, means for disengaging said 45 member from the web perforation, and means for moving said member in the plane of the web into engagement with an imperforate part thereof.
7. In a machine of the character described, the combination of means for feeding a web, with a registering member adapted to enter a perforation in the web, means for disengaging said member from the web, and spring means for moving said member 50 in the plane of the web into engagement with an imperforate part thereof.
8. In a machine of the character described, the combination of means for feeding a web, with a spring-actuated registering member adapted to enter a perforation in the web and a spring device for moving said member in the plane of the web into engagement with an imperforate part thereof.
9. In a machine of the character described, the combination of means for feeding a web, with a feeler device movable longitudinally and transversely of its length adapted to enter a perforation in the web and means actuated by the movement of the feeler device for releasing the feeding means 75 from the web.
10. In a machine of the character described, the combination of means for feeding a web, with a spring actuated rock shaft mounted in fixed relation to said feeding means, suitable feeler registering fingers supported by said rock shaft in operative relation to the path of the web, said fingers being movable upon their support in the web path and normally engaging the web to hold 80 said shaft against movement with the fingers in position to engage web perforations.
11. In a machine of the character described, the combination of means for feeding a web, with a registering member adapted to enter a perforation in the web, means actuated by a movement of said registering member for rendering the feeding means inactive, means for disengaging said member from the web, and means for moving said 85 member in the plane of the web into engagement with an imperforate part thereof.
12. In a machine of the character described, the combination of a pair of feed rolls, means for moving one of said rolls 100 relatively to the other, suitable feeler registering fingers supported above the path of a web, a spring actuated rock shaft supporting said fingers, said fingers being transversely movable upon their support and normally engaging the web to hold said shaft against movement with the fingers elevated and means actuated by said shaft for operating said roll moving means.
13. In a machine of the character described, the combination of a pair of feed rolls, means for moving one of said rolls 105 relatively to the other, suitable feeler registering fingers supported above the path of a web, a spring actuated rock shaft supporting said fingers, said fingers being transversely movable upon their support and normally engaging the web to hold said shaft against movement with the fingers elevated, manually operated means for rocking said 110 shaft to elevate said fingers and re-set said feed rolls in their operative relation, and means actuated by said shaft for operating said roll moving means.
14. In a machine of the character described, the combination of suitable feeding means, with a rock shaft carrying rock-arms, feeler registering fingers supported by said rock-arms, suitable guides for said fingers, springs engaging said fingers and tending to 115

move them transversely of their length in said guides.

23. In a machine of the character described, the combination of means for feeding a perforated web, with a registering feeler device movable perpendicularly to the web path into and out of a web perforation and parallel with the web path when released from the web perforation, said feeler device being normally supported by an imperforate part of the web and moved thereby in the web path prior to each registering operation.
- 10 24. In a machine of the character de-

scribed, the combination of means for feeding a perforated web, with a registering 15 feeler device movable perpendicularly to the web path into and out of a web perforation and parallel with the web path when released from the web perforation, said feeler device being normally supported by an imperforate 20 part of the web and moved thereby in the web path prior to each registering operation, and a stop for limiting the movement of the registering device in the web path.

HERBERT L. ROBERTS.
